UNITED STATES PATENT OFFICE.

GEORGES LADOIRE, EUGENE WILMOUTH, FRANCOIS VARILLON, AND LOUIS BATAYRON, OF LYON, FRANCE.

REELING OR WINDING MACHINE.

Application filed February 20, 1926, Serial No. 89,671; and in France February 28, 1925.

This invention relates to improvements in reeling or winding machines.

Reeling or winding is still often done by hand, the operator mounted on the frame giving the wire from the drawing mill an alternate movement from side to side with his wrist as it winds on to the bobbin or reel. This operation is very tiring and as it must be done regularly it accounts for a considerable loss.

This invention comprises an automatic distributor for the winding of bobbins characterized in that the wire before being wound on to the bobbin passes over a guide pulley carried by a rod receiving a transverse movement alternately from side to side from a lever having an adjustable fulcrum to vary the amplitude of this movement, this lever being itself operated from a cam surface rotating at a speed proportional to that of the bobbin.

This automatic winding of the bobbin is distinguished from automatic winding apparatus at present in use in that it is of reduced and compact form and capable of being fitted to any existing winding machine. It is usually mounted on a pedestal on this latter.

The invention will be described with reference to the accompanying drawings.

Fig. 1 is a front view with the cover removed.

Fig. 2 is a side view, the cover being in section.

Fig. 3 is a view from the back.

The wire coming from the drawing mill passes over a guide pulley *a* and is wound on to a reel *b* mounted on a frame and given a rotary motion. This pulley *a* is mounted on an arm *c*, sliding freely in slides *d* on a frame *e*, to which one end of a lever *f* fulcrumed slidably about a stud *g*, is pivoted. The other end of this lever is pivoted by a pivot *h* to a member *h* which slides in bearings *i* and bears against a heart shaped cam *j*. Said pivot *h* operates in a slot *f'* with which the member *f* is provided. The cam *j* is mounted on a spindle *k* on which a worm wheel *l*, gearing with a worm *m* is also mounted. The worm *m* is driven by a rope passing over a driving pulley *o* the rope also passing over a pulley *p* mounted on a system of pivoted levers *q* which keeps it tensioned.

A helical spring *r* surrounding and affixed

to a spindle *s* applies pressure to one end of the lever *f* causing the other end to keep the member *h* constantly in contact with the cam *j*.

The cam *j* gives a backward and forward movement to the member *h*, when the pulley *o* is driven, this movement being transmitted through the arms of the lever *f* to the arm *c* of the guide pulley *a*.

In order to give a movement to the arm *c* which will correspond to the size of the reel the throw of the ends of the lever *f* is variable; the stud *g* on which it is fulcrumed is carried by a bracket *t* mounted on a screw *u*. By rotating this screw *u* the bracket *t* and stud *g* can be brought nearer to or further from the arm *c* thereby reducing or increasing the travel of this arm.

The guide pulley *a* is mounted on the arm *c* by a rod *v* sliding in a sleeve *w* carried by the arm. A spring *y* is inserted on the rod *v* between the sleeve *w* and a collar at its upper end so that the tension of the wire being wound can be regulated.

In order to adjust the pulley *a* to the centre of the reel *b* the apparatus can be moved bodily transversely, the frame *e* being formed with two projections *z* which slide in sockets in the member *s* affixed by a projecting clamp *5* to the machine pedestal. A screwed rod *2* affixed to the frame *e* passes through the member *s* so that by the rotation of the rod *2* the apparatus can be moved bodily into the correct position.

A cover *4* held in position by a screw *90* protects the mechanism from dust.

This apparatus is in a very compact form and can be used in conjunction with an automatic stop motion if the wire should break and is very easily assembled without alteration, on the pedestals of existing winding machines. The compact shape renders it little in the way and is thus particularly practical.

What we claim as our invention and desire to protect by Letters Patent is:—

1. An automatic distributor for existing, winding or reeling machines comprising a guide pulley over which the wire to be reeled passes, a frame, an arm carrying the pulley, bearings on the frame in which the arm slides, a lever pivoted on the arm, a stud on the frame about which the lever pivots, a member pivoted to the lever and sliding on the frame, a spindle carried by

the frame, a cam mounted thereon against which the sliding member bears, a worm wheel mounted on the spindle, a second spindle carried by the frame, a worm carried thereby with which the worm wheel gears, a pulley mounted on the second spindle by which the worm is driven and means for mounting the frame on the winding machine and means for adjusting it with respect thereto.

2. An automatic distributor for existing winding or reeling machines as in claim 1 in combination with a vertical screw carried by the frame on which the fulcrum for the lever is mounted to vary the travel of the guide pulley.

3. An automatic distributor for existing winding or reeling machines comprising a guide pulley over which the wire to be reeled passes, a rod supporting the guide pulley, a sleeve in which the rod slides, a spring mounted on the rod and a screw for varying the tension on the spring to adjust the

tension on the wire, a frame, an arm carrying the sleeve, bearings on the frame in 25 which the arm slides, a lever pivoted on the arm, a stud on the frame, about which the lever pivots, a member pivoted to the lever and sliding on the frame, a spindle carried by the frame, a cam mounted thereon against 30 which the sliding member bears, a worm wheel mounted on the spindle, a second spindle carried by the frame, a worm carried thereby with which the worm wheel gears, a pulley mounted on the second 35 spindle by which the worm is driven and means for mounting the frame on the winding machine and means for adjusting it with respect thereto.

In witness whereof we affix our signatures.
